CLAIM

The ornamental design for an orthopedic knee brace, as shown and described.

DESCRIPTION

FIG. 1 is an isometric view of an orthopedic knee brace showing my new design, the broken lines are for illustrative purposes only and form no part of the invention;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof; and,

FIG. 7 is a bottom plan view thereof.
